UNITED STATES PATENT OFFICE.

FRANK THORNTON, JR., OF PITTSBURGH, PENNSYLVANIA, ASSIGNOR TO WESTINGHOUSE ELECTRIC AND MANUFACTURING COMPANY, A CORPORATION OF PENNSYLVANIA.

SAD-IRON STAND.

1,161,167.

Specification of Letters Patent. Patented Nov. 23, 1915.

Application filed July 17, 1912. Serial No. 710,030.

To all whom it may concern:

Be it known that I, FRANK THORNTON, Jr., a citizen of the United States, and a resident of Pittsburgh, in the county of 5 Allegheny and State of Pennsylvania, have invented a new and useful Improvement in Sad-Iron Stands, of which the following is a specification.

My invention relates to supporting structures for heated bodies, and it has particular reference to devices that are adapted to support electrically heated sad irons or similar implements when the same are not in use.

15 One of the objects of my invention is to provide a device of the above-indicated character which shall be simple, compact and durable in construction, inexpensive to assemble and manufacture, and particularly 20 adapted to prevent the conduction or transmission of heat from the heated body to the surface upon which the stand rests.

According to my invention, I provide a supporting structure of this general class 25 which comprises a plurality of punched or pressed sheet metal parts which may be formed at relatively small expense, and may be readily assembled and united in such manner as to effectively perform their intended functions and also provide a stand 30 which shall be particularly strong and adapted to withstand careless and rough usage.

In the accompanying drawing, Figure 1 35 is a side elevational view of a supporting structure embodying my invention, and including an electrically heated sad iron in position thereon, and Fig. 2 is a plan view of the device shown in Fig. 1 with the sad iron and a portion of said device removed 40 for the sake of clearness. Figs. 3 and 4 are views respectively similar to Figs. 1 and 2 of a modified form of my invention, a portion of Fig. 3 being shown in section.

45 Referring particularly to Figs. 1 and 2, a heated body 1, which is shown for illustrative purposes as an electrically heated sad iron, but which may constitute any other heated implement, rests upon a supporting structure or stand 2. The stand 2 50 comprises a plurality of plates 3, 4 and 5 which are preferably constructed of sheet metal and which are substantially of the same shape or contour as the sad iron 1, or

other body which the stand 2 is adapted to 55 support.

The plate 3 constitutes a supporting plate for the sad iron 1, and its outer side edges 6 are disposed at substantially right angles to the main portion thereof to form an upwardly projecting outer flange which is 60 adapted to maintain the sad iron in position. A portion 7 at the heel of the plate 3 is slightly inclined with respect to the main body of the plate in order to assist in sliding the device 1 into its proper position upon the stand in case it is hastily or carelessly placed thereon. A plurality of downwardly 65 projecting integral spherically curved portions 8 are also provided upon the plate 3, 70 one of which is conveniently located near the toe of the plate while the other portions are located at the heel thereof. Obviously, the plate 3 may be constructed and formed 75 in any well known and desired manner, although I find it preferable to punch the same out of a sheet metal blank and to press the spherically curved projecting portion 8 therein in accordance with well known practice. In this manner, the necessary work 80 may be accomplished with facility and comparatively small expense, and the plates thus produced are particularly adapted for the purposes intended.

Plate 5 constitutes a supporting base, and 85 although shown somewhat larger in size than the plate 3, to accommodate a larger iron, it is otherwise similar and is constructed in the same manner as that already described. The plate 5 embodies downwardly 90 projecting outer flanges 6^a, an inclined end flange 7^a, and a plurality of upwardly projecting integral spherically curved portions 8^a which are correspondingly located with respect to the spherically curved portions 8 95 of the upper plate 3.

The intermediate plate 4, which constitutes a baffle or a heat-radiating plate that may or may not be used, rests upon the upwardly projecting portions 8^a, and, disposed 100 upon the plate 4, is the upper supporting plate 3 having its downwardly projecting integral portions 8 located directly above the projecting portions 8^a in such manner that the several plates are in contact or engagement only at three points, which, by reason of the shape of the projecting portions 8 and 8^a, are of comparatively small area. In 105

order to secure the several parts rigidly together to form a strong and unitary structure, a plurality of rivets 9, or other suitable means, are employed, said rivets 9 or 5 other means being located substantially at the points of engagement.

It should, of course, be understood that the plates 3, 4 and 5 may or may not be of substantially the same size, but, in many 10 cases, it is desirable to make them of somewhat different sizes, as shown in the drawing, in order that the stand may be reversible, whereby it is adapted to accommodate different sizes of sad irons or other implements.

When the stand is used for supporting a heated body, such as the electrically heated sad iron 1, inappreciable amounts of heat are transmitted to the supporting base plate 5 by reason of the fact that a minimum 20 number of engaging points are provided, and said points are of comparatively small area, so that very little heat is transmitted therethrough. Furthermore, the intermediate 25 baffle or radiating plate 4 serves to obstruct the direct downward radiation of heat from the heated body 1 and also tends to radiate such heat freely into the atmosphere. Attention is also directed to the 30 fact that the base plate 5 is adapted to engage any convenient supporting surface (not shown) only at the bottom edges of the side flanges 6^a. Thus an air space is provided beneath the base plate 5 which 35 assists in cooling the same and preventing undesirable heating of the supporting surface. Moreover, a very small portion of the base plate 5 is in actual engagement with the supporting surface, and a large portion 40 of the plate is exposed for radiation so that the amount of heat actually transmitted to the supporting surface is comparatively negligible.

Referring now to Figs. 3 and 4 of the 45 accompanying drawing, an electrically heated body 1 is supported upon a stand or structure 2 which comprises an upper supporting plate 3 and a lower base plate 5 which are similar in construction to the 50 plates 3 and 5 shown and described with reference to Figs. 1 and 2, and which are disposed the one upon the other and secured together in a manner similar to that which has already been set forth, and on account 55 of this similarity in structure and assemblage, no further detailed description thereof is deemed necessary. It should be noted, however, that the upper plate 3 is provided with a plurality of upwardly projecting spherically curved portions 10, one of which is disposed at the toe of the stand 2, while the remaining projections are symmetrically located at the heel thereof. The 60 projections 10, just referred to, serve to support the heated body 1 upon three points 65

of very small area so that the direct conduction of heat to the plate 3 is very small. The plate 5 is also provided with similarly disposed downwardly projecting spherically curved portions 10^a which are adapted 70 to serve the purpose of supporting a heated body 1 when the stand 2 is reversed in position so that the plate 5 constitutes the upper supporting plate.

In many cases, it may be found unnecessary to provide an intermediate baffle or radiating plate such as is shown in Figs. 1 and 2, and no such plate is employed in the supporting structure shown in Figs. 3 and 4, the upper and lower plates 3 and 5, respectively, being in direct intimate engagement through their oppositely projecting portions 8 and 8^a. It will, of course, be understood that, if desired, an intermediate plate such as is shown in Figs. 1 and 2, 80 85 may be inserted between the upper and lower plates 3 and 5 of the supporting stand shown in Figs. 3 and 4, or it may be found desirable to construct the supporting stand in accordance with Figs. 1 and 2 but 90 with the intermediate radiating plate omitted.

Obviously, many other variations and modifications in the structural details and arrangement and location of parts may be 95 effected without departing from the spirit and scope of my invention, and I desire that only such limitations shall be imposed as are indicated in the appended claims.

I claim as my invention:

1. A stand for supporting heated bodies comprising a plurality of plates having substantially plane surfaces and having correspondingly disposed integral curved portions that severally coöperate, the one with 105 the other, in pairs, and means for securing said plates together.

2. A stand for supporting heated bodies comprising a plurality of similar plates having substantially plane surfaces and having correspondingly disposed integral curved portions that project laterally beyond the adjacent surfaces of the plates, into proximity to each other, and an intermediate plate interposed between the curved 115 portions of said first mentioned plates.

3. A sad iron stand comprising a sheet metal base plate having a plurality of upwardly projecting integral portions and a substantially plane portion, a second sheet metal plate resting thereon, a third sheet metal plate having correspondingly located downwardly projecting integral portions adapted to rest upon said second plate directly above the first-mentioned integral 120 portions, and means for securing said parts together at their points of contact.

4. A supporting structure for heated bodies comprising a plurality of sheet metal plates having correspondingly and opo- 130

sitely disposed pressed portions and an intermediate plate adapted to engage said pressed portions at a plurality of points, and means for rigidly uniting said parts at the points of engagement.

5. A sad iron stand comprising a sheet metal base plate having downwardly projecting edges and a plurality of upwardly projecting integral pressed portions, a radiating plate resting on said portions, and a sheet metal supporting plate having correspondingly located downwardly projecting

10 portions adapted to rest upon said radiating plate, and a plurality of rivets for uniting said parts together at their engaging portions.

In testimony whereof, I have hereunto subscribed my name this 6th day of July 1912.
